(57) **CLAIM**

The ornamental design for a portable device case, as shown and described.

DESCRIPTION

FIG. 1 is a perspective view of the new design for a portable device case in accordance with a first embodiment of the present invention;

FIG. 2 is a front view of the portable device case shown in FIG. 1;

FIG. 3 is a right view of the portable device case shown in FIG. 1;

FIG. 4 is a left view of the portable device case shown in FIG. 1;

FIG. 5 is a top view of the portable device case shown in FIG. 1;

FIG. 6 is a bottom view of the portable device case shown in FIG. 1;

FIG. 7 is a rear view of the portable device case shown in FIG. 1;

FIG. 8 is a perspective view of the new design for a portable device case in accordance with a second embodiment of the present invention;

FIG. 9 is a front view of the portable device case shown in FIG. 8;

FIG. 10 is a right view of the portable device case shown in FIG. 8;

FIG. 11 is a left view of the portable device case shown in FIG. 8;

FIG. 12 is a top view of the portable device case shown in FIG. 8;

FIG. 13 is a bottom view of the portable device case shown in FIG. 8; and,

FIG. 14 is a rear view of the portable device case shown in FIG. 8.

The broken lines depict unclaimed environmental features and form no part of the claimed design.

1 Claim, 10 Drawing Sheets
